(Model.)

I. A. SHAW.
COMBINATION LOCK.

No. 404,568.

Patented June 4, 1889.

UNITED STATES PATENT OFFICE.

IRVIN A. SHAW, OF KINSLEY, KANSAS.

COMBINATION-LOCK.

SPECIFICATION forming part of Letters Patent No. 404,568, dated June 4, 1889.

Application filed June 12, 1888. Serial No. 276,820. (Model.)

To all whom it may concern:

Be it known that I, IRVIN A. SHAW, of Kinsley, in the county of Edwards and State of Kansas, have invented a new and Improved 55 Combination-Lock, of which the following is a full, clear, and exact description.

The object of the invention is to provide a new and improved combination-lock, which is very simple and durable in construction, 10 and in which the operator is guided by the sound of a spring engaging a turning ratchet-wheel.

The invention consists of certain parts and details and combinations of the same, as will 15 be fully described hereinafter, and then pointed out in the claims.

Reference is to be had to the accompanying drawings, forming a part of this specification, in which similar letters of reference indicate 20 corresponding parts in all the figures.

Figure 1 is a face view of the improvement. Fig. 2 is a like view of the same with the outer plate removed. Fig. 3 is a similar view with the inner plate removed. Fig. 4 is a sectional 25 plan view of the same on the line xx of Fig. 1, and Fig. 5 is a cross-section of the same on the line yy of Fig. 1.

The improved combination-lock A is provided with the usual locking-bolt B, held to 30 slide in a suitably-constructed casing C, consisting, principally, of a plate C' fastened to door D, and of a casing C² secured to the said plate C'. The outer end of the locking-bolt B is provided with the bevel B', adapted to 35 engage the removable catch-plate E', held to slide in the keeper E, secured to the door-jamb D'. In the bottom edge of the locking-bolt B is formed a notch B², which engages the end of a pin F, secured to the shaft G, 40 mounted to turn in the casing C, and passing through the door D, carrying at its outer ends the usual door-knobs H. The outward movement of the pin F is limited by a stop-pin F' secured to the plate C', and the inward movement 45 of the locking-bolt B is limited by a projection B³, formed on the bolt B and adapted to engage the said stop-pin F'. At the inner end of the bolt B is formed a projection B⁴, on which is coiled a spring I, resting with its 50 outer end against the casing C and with its other end against the said bolt B, so that the latter is pressed outward by the spring I.

In the locking-bolt B are formed one or more transversely-circular openings B⁵, in each of which is fitted to turn a tumbler J, provided with a slot J', extending at one end to the periphery of the tumbler. Into this slot J' fits the flat plate K, provided with a slight extension K' of the same size and form and adapted to pass into a slot B⁶, formed in the bolt B, and being a continuation of the circular opening B⁵.

The flat plate K is formed on the shaft K², extending through an opening D² in the door D, to the outside of the latter, and having its bearing in the inner plate C' of the casing C and in the outer plate C², secured to the outside of the door D. On the outer end of the shaft K² is secured a small knob K³. On the other end of the flat plate K is formed a collar K⁴, which has its bearings in the casing C², and from the said collar K⁴ projects the reduced shaft K⁵, which is threaded on its outer end, on which screws a small knob K⁶, similar to the knob K³ above mentioned. 75

On the inner part of the shaft K⁵ is fitted a ratchet-wheel L, the face of which rests against the collar K⁴, and said wheel is secured on the said shaft K⁵ by screwing the knob K⁶ tightly against the said ratchet L, so that the latter 80 is clamped on the collar K⁴ by the knob K⁶, whereby the said ratchet-wheel L turns with the shaft K⁵, the plate K, and the shaft K². The teeth of the ratchet-wheel L are engaged by a spring N, secured by its end to a suitable 85 post held on the casing C². The ratchet-wheels L and the springs N are inclosed in a covering plate or casing C⁴, secured to the outer plate C² of the casing C, as is plainly shown in Fig. 4. In each ratchet-wheel several teeth are broken out, so as to form on the 90 periphery of the wheel a space L', as shown in Fig. 2.

The operation is as follows: The springs N permit their respective ratchet-wheels L to be 95 turned only in the direction of the arrow a'. By making one complete revolution of the ratchet-wheel L the free end of the spring N comes in contact with the space L' and then with the several teeth. When the spring 100 passes over the space L', no sound is heard from the outside; but when the spring passes over the several teeth the usual click is heard. The number of teeth in the ratchet-wheel L

- is known to the operator, and the ratchet-wheel is set to any desired number of teeth, counting from the space L' in a forward direction, as indicated by the arrow a' . The ratchet-wheel is set by loosening the knob K^3 or K^4 and then turning the shaft K^2 so that the flat part K assumes a certain relative position to the slot B^6 in the locking-bolt B —that is, when, for instance, the ratchet-wheel L , on the right-hand side of Fig. 2, is set to eleven teeth the plate stands in line with the slot B^6 . The other ratchet-wheel L , at the left in Fig. 2, is set to six teeth, so that the combination of the entire lock, as represented in the drawings, is set to six and eleven.
- When the flat parts K and K' are in the positions shown in Figs. 2, 3, and 4, they register with the slots B^6 and permit the operator on turning the knob H , to slide the bolt B forward or backward, so as to open or close the door; but when the other knob K^3 or K^6 is turned from the inside or outside of the door, so that the respective springs N engage other teeth than 6 and 11 on the ratchet-wheels L , the flat parts K and K' stand at an angle to the slots B^6 , and hence prevent the sliding movement of the bolt B . The door is then in a closed position, and the front end B' of the bolt B engages the catch E .
- When the operator desires to open the door from either the outside or inside after the ratchet-wheels L have been displaced, as above described, he first turns either the inside or outside knob K^3 or K^6 until the click is no longer heard—that is, when the spring passes through the space L' . Then the operator counts the number of clicks until, on the left knobs K^3 and K^6 , he counts six, and on the other knobs K^3 and K^6 on the right he counts eleven clicks, which indicates that the ratchet-wheels L and springs N stand in the position shown in Fig. 2, and the flat parts K and K' of both shafts K^2 also stand in line with the longitudinal slots B^6 of the locking-bolt B . The operator can then turn the knobs H so that the pin F of the shaft G , engaging the notch B^2 of the locking-bolt B , moves the latter inward, and the slot B^6 passes over the flat part K .
- When the operator releases the knob H , the spring I forces the bolt B outward again, so that when the door is closed the beveled end B' passes over and onto the catch E , after which the operator presses the said knobs K^6 , so that the springs N engage different teeth of the ratchet-wheel L , whereby the flat parts K and K' are thrown into an angular position in relation to the slots B^6 in the bolt B . The door is then locked.
- Thus it will be seen that the operator can set the ratchet-wheels L to any desired combination, and the door can be locked or unlocked from either the inside or the outside.
- I do not limit myself to the special construction of the knob-shaft G with its pin F , as other devices—such as a slide—may be

used to operate the bolt B . If there is no necessity for opening a door from the inside, then the inner knob H is entirely dispensed with. For heavy doors I may make the bolts ⁷⁰ B double, and in order to complicate the combination more tumblers may be added. If the catch-plate E' on the inside of the door-frame is removed, the door may be opened from the inside, which is necessary in case of ⁷⁵ fire and strangers who do not know the combination. The lock may be used in a mortise-lock as well as a case-lock.

Having thus fully described my invention, I claim as new and desire to secure by Letters ⁸⁰ Patent—

1. The combination, with a sliding bolt having a longitudinally-extending slot and a circular opening communicating with the inner end of said slot, of a shaft having a flat part, a circular tumbler having a slot receiving said flat part and turning in said circular opening, whereby, when said flat part and tumbler-slot are perpendicular to the bolt-slot, the bolt will be locked and when turned ⁸⁵ flatwise into the plane of the bolt-slot the bolt may be retracted, said tumbler sliding with the bolt, substantially as set forth.

2. In a combination-lock, the combination, with a locking-bolt provided with a circular slot connecting with a longitudinal slot, of a shaft provided with knobs and having a flat part, a tumbler held on the said flat part and fitting into the circular slot of the locking-bolt, a ratchet-wheel held on the said shaft and turning with it, and a spring engaging with its free end the teeth of the said ratchet-wheel, substantially as shown and described. ⁹⁵

3. In a combination-lock, a locking-bolt provided with a circular slot continuing into a longitudinal slot, and a knob-shaft provided with a pin for operating said locking-bolt, in combination with a shaft provided with a knob on the inside and on the outside of the door, and also having a flat part ¹⁰⁵ adapted to engage the longitudinal slot of the said locking-bolt, a slotted tumbler held on the said flat part and fitting into the circular slot of the said locking-bolt, a ratchet-wheel held on and turning with the said shaft ¹¹⁰ and provided with a space in its periphery, said space being formed by the breaking out of several teeth, and a spring engaging with its free end the teeth and space of the said ratchet-wheel, substantially as shown and ¹¹⁵ described.

4. In a combination-lock, a locking-bolt provided with a circular slot continuing into a longitudinal slot, and a knob-shaft provided with a pin for operating said locking-bolt, and a spring bearing against said locking-bolt, in combination with a shaft provided with a knob on the inside and on the outside of the door, and also having a flat part adapted to engage the longitudinal slot ¹²⁵ of the said locking-bolt, a slotted tumbler held on the said flat part and fitting into the

circular slot of the said locking-bolt, a ratchet-wheel revoluble on the said shaft and provided with a space in its periphery, said space being formed by breaking out several teeth, a
5 knob screwed on the shaft against said ratchet-wheel and clamping it in place, and a spring engaging with its free end the teeth and space of the said ratchet-wheel, substantially as shown and described.
